UNITED STATES PATENT OFFICE.

AXEL ANDERSON, OF ATTLEBOROUGH, MASSACHUSETTS.

WRENCH.

SPECIFICATION forming part of Letters Patent No. 498,348, dated May 30, 1893.

Application filed April 3, 1893. Serial No. 468,778. (No model.)

To all whom it may concern:

Be it known that I, AXEL ANDERSON, of Attleborough, in the county of Bristol and State of Massachusetts, have invented certain new 5 and useful Improvements in Wrenches; and I do hereby declare that the following is a full, clear, and exact description thereof, reference being had to the accompanying drawings, and to the letters of reference marked 10 thereon, which form a part of this specification.

This invention relates to improvements in wrenches of that class especially designed for bicycle use, which requires great strength with lightness, and small bulk, with a wide 15 range of opening capacity. It is fully illustrated both in manner of construction and operation in the accompanying drawings.

Figure 1, shows a side view of the wrench partly open. Fig. 2, is an edge view of the 20 same. Figs. 3, 4, 5, 6 and 7, represent the parts separate, as will be explained herein-after.

The invention consists of the following parts: two short, round bars, *a*, *a*, Fig. 3, made preferably, of what is known as cold rolled or compressed steel, because of its condensation and increased strength from the way it is made. These bars are slightly reduced in size for a 25 short distance from their ends, by milling, to form slight shoulders *c*, *c*. A head or outer jaw *A*, (Fig. 5) is made of square bar steel, with one side milled off to the usual shape of the outer jaws of wrenches, and the two holes 30 *s*, are drilled in it, one near its large end and the other near its middle, of proper size to fit on the milled parts of the bars *a*, and another smaller hole *s'* is drilled part way through the bar, midway between the holes *s*, *s*, to receive one end of the screw *d*. Fig. 5, shows side 35 and top views of the jaw. The inner jaw *b*, of which Fig. 6, shows inside and outside views, is made of steel casting, or by drop forging, and is similar in shape to the outer jaw, with the addition of a short sleeve *n*, that 40 projects out on one side around one of the holes which are made through the jaw to exactly correspond with the holes *s*, described in the outer jaw, only enough larger to allow the bars *a*, to slide easily in them. A hole *v*, 45 is made through this inner jaw, to correspond with the step hole *s'*, in the outer jaw, and a screw thread is made in the hole to receive

the screw *d*. A light cross piece or block *j*, is made with two of its corners rounded (see top and edge views Fig. 7). Two holes *o*, *o*, 55 55 are made in the edge of this block, corresponding in size and position with the holes *s*, *s*, in the outer jaw *A*, to receive the milled parts of the bars *a*, *a*. A screw *d*, Fig. 4, has about one-half of its length reduced somewhat, and a screw thread made on it to fit the thread in the hole *v*, in jaw *b*, and the other half of the piece *t*, larger in diameter, has a knurled figure made on it, or is otherwise roughened, to enable the thumb to easily 60 turn it when the wrench is held in the hand. The ends of the screw *d*, are milled down to form steps or journals to fit in the holes *s'* and *i*, in the jaw *A*, and block *j*, respectively. 65

The wrench is put together by first putting 70 an end of one bar *a*, in one of the holes *s*, in the jaw *A*, and an end of the other bar *a*, in the other hole *s*, and riveting them on the outside, the holes being countersunk on that side for that purpose. The jaw *b*, is then put on 75 the bars *a*, and slid up toward the jaw *A*, and the screw *d*, is turned in through the hole *v*, until its smaller end enters the step hole *s'*. Then the block *j*, is put on the free ends of the 80 bars *a*, which enter the outer holes *g*, in the block, and are held there by having pins put through them and the block. The outer end of the screw *d*, is at same time entered in the hole *i*. The wrench is then ready for use. It is held across the inside of the hand on the 85 fingers, with the thumb resting on the roughened part *t*, of the screw, and by pushing the thumb slightly in either direction, the screw *d*, will be turned, and the jaws opened or closed, according to the direction the thumb 90 is moved. The length of the rough part *t*, makes it easy to find it with the thumb, and gives a large surface to turn the screw by.

The bars *a*, and block *j*, form the handle, and reduce the weight of the wrench one- 95 third, as compared with wrenches of like capacity with parallel bars that slide into a solid handle, and its length is reduced one-half, as compared with wrenches with parallel bars and a handle beyond them, as in Patent No. 100 170,492, granted to H. Port, November 30, 1875. These features especially adapt it for use as a bicycle and pocket wrench.

Having thus described the construction and

characteristics of my improved wrench, what I claim as my invention is—

A wrench consisting of a pair of round bars having one end of each bar made fast in a head or outer jaw, and their other ends in a short block, a loose jaw arranged to slide on said bars, and a screw located between said bars and having journal steps in the outer jaw, and the end block, with a screw thread made

on one part of it, fitting in an internal screw thread made in a hole in the inner jaw, and having a larger portion knurled or otherwise roughened, the bars and block forming the handle, substantially as set forth.

AXEL ANDERSON.
